UNITED STATES PATENT OFFICE.

JOSEPH C. COULOMBE, OF LOWELL, MASSACHUSETTS.

CARBURETER.

1,254,659.

Specification of Letters Patent. Patented Jan. 29, 1918.

Application filed December 3, 1914. Serial No. 875,304.

To all whom it may concern:

Be it known that I, JOSEPH C. COULOMBE, a citizen of the United States, and a resident of Lowell, in the county of Middlesex and State of Massachusetts, have invented certain new and useful Improvements in Carbureters, of which the following is a full, clear, and exact description whereby any one skilled in the art may make and use the same.

The invention relates to carbureters and while it may be used advantageously in any carbureter designed, it is particularly well adapted for use in the type of carbureters having no moving valve parts for varying the attenuation of the mixture.

The object of the invention is to provide a simple and compact device which will be effective and self-regulating for all engine speeds and will always produce a proper mixture.

A further object is to provide a series of chambers and by-passes for liquid fuel by which a proper mixture can always be secured under the most unusual speed variations.

A still further object is to provide arrangements of fuel ducts and controls by which a proper mixture will be secured for easy starting of the engine; for rapid changes from very slow speeds with the carbureter throttled; up to immediate high changes with the throttle wide open and for the various speed changes in the engine from the lowest to the highest speed.

Referring to the drawings—

Figure 1 is a plan view of a form of the carbureter.

Fig. 2 is a view in side elevation.

Fig. 3 is a partial vertical cross-sectional view on the line 3—3 of Fig. 1.

Fig. 4 is a similar sectional view on the line 4—4 of Fig. 1.

Fig. 5 is a detail section along the line 5—5 of Fig. 1.

Fig. 6 is a detail view of the stand-pipe quill.

Fig. 7 is a detail view of the adjustable standpipe.

It has been common practice to employ in carbureters automatically actuated valves for controlling the volume of flow of fuel from the float feed chamber of constant level to the venturi or aspirating nozzle of the

carbureter. Such devices commonly employed the varying suction induced by the engine upon the carbureter for operating the valves.

The present invention has to do with non-automatic valves and is intended to provide a carbureting mechanism which will operate under all engine speed changes and varying suction effects to give the required mixture of fuel and air for forming a correct explosive charge for the engine cylinders. The invention as applied to the drawings hereinafter described illustrates a form of carbureter having non-moving parts, that is, non-moving valve mechanisms which are dependent upon engine suction. The term "non-moving parts" is applied to distinguish from types of devices above referred to in which the valves are automatically moved to control the flow of fuel dependent upon the suction induced in the carbureter. The present invention has to do with a carbureter of the non-moving valve type provided with ducts, channels and chambers for the fuel which will operate independently or collectively and coöperate to give a proper mixture for all conditions of use.

In the accompanying drawings, there is a main casting 1 having an inlet opening 2 and a throttle opening 3. The inlet opening and outlet opening are connected by the venturi 4 and the inlet 2 has a valve of the butterfly type 5 which is normally held open by a spring 6 but may be closed by the lever 7 for starting the engine when it is cold.

The outlet 3 is controlled by a suitable throttle valve 8 herein shown as of the butterfly type suitably connected with an operating lever 9. On the lower side of the casting 1, there is a suitable seat 10 against which is fitted a cup-like bowl 11, which provides the float feed chamber 12. The lower part of the bowl is held against a shoulder 13 formed on the central opening portion of the casing and is secured in place by a nut 14.

The float feed chamber 12 is provided with a float 15 which, through a pivoted connection 16 actuates the inlet valve 17 that controls the oil inlet passage 18.

At the lower end of the float feed chamber, there is a channel 19 which communicates with a central chamber 20 formed in the lower end of the casting and centrally

of the carburetor mechanism. The chamber 20 forms a well, which is separated from an oil chamber 21 by a "quill" 22, which has a shoulder 23, at its lower end fitting upon a shoulder 24 formed by the difference in diameter between the chamber 20 and the chamber 21.

The chamber 21 is enlarged at its upper end as at 25 and opens directly into the venturi about the "quill" 22.

The "quill" 22 is provided with openings 26, certain of the openings being located within the chamber 21 and others extending into the opening of the venturi. The "quill" 22 has an enlarged screw-threaded shank 27 which is screwed into the central orifice of the carburetor casting at its upper end. The quill performs the double function of providing a wall between the chambers 20 and 21, outlets into the venturi, then into the chamber 21 and a support for the adjustable stand-pipe 28. This stand-pipe has a central opening 29 open at its upper end to the atmosphere through a relatively small port 30 and connected directly with the chamber 20. It is also provided with annular grooves and rings 31, 32. In the grooves are perforations 33 so that communication may be opened between the perforations 26 of the quill 22 and the interior opening 29 of the stand-pipe. The upper end of the stand-pipe 28 is threaded into the quill 22 and may be adjusted so as to bring its perforations 33 into and out of greater or less registering position with the perforations 26 of the quill by turning the knurled nut 34. A portion of the threading of the stand-pipe 28 is cut open as at 35 to form an annular groove and extending through the quill 22 and into this annular groove is a stop screw 36. The groove is made of a sufficient length to permit moving the stand-pipe 28 into full registering position as to its perforations 33 and the perforations 26 of the quill or completely out of registering position therewith. At the same time, a sufficient pressure may be exerted through the stop screw 36 to insure maintaining any given adjustment which has been made by turning the knurled nut 34 and stand-pipe 28.

It will be observed that the float feed chamber and the stand-pipe are both open to atmosphere and therefore there will always be a constant fuel flow from the float feed chamber to the stand-pipe, due to the difference in "head" or level between the surface of the fuel and the opening of the passage 19.

Ordinarily, the chamber 21 will be filled with fuel to the height of the constant level of the float feed chamber by percolation of the fuel through the registering openings 33, 26 of the stand-pipe and quill and the stand-pipe 28 will be filled with fuel to the same

level except as increased suction will raise the level in the stand-pipe.

Suction in the venturi causes a slight suction in the stand-pipe 22 and therefore the fuel will rise in the stand-pipe and as the column of fuel comes opposite the registering openings 33, 26, suction in the venturi will carry the fuel along with the air to the engine.

When the throttle is practically closed, there is not a sufficient suction in the venturi to pick up a sufficient quantity of fuel. There is therefore provided a by-pass duct 37 which communicates with the chamber 21 and extends to the throttle valve where it opens through a port 38 (see Figs. 1, 2 and 4). This by-pass picks up the fuel from the annular well or chamber 21, 25, the latter being directly connected with the venturi. It is therefore able to work in two ways. At the very low speeds when the engine is running practically idle, the suction will pick up a sufficient quantity of fuel through the by-pass as the suction effect is greatest upon it owing to the throttle being nearly closed. As the throttle is opened, however, the suction increasing becomes sufficient in the venturi to pick up fuel from the well or chamber opening 25. The well or chamber 25 is also efficient to aid in starting. In Fig. 3, there is illustrated an over-flow 39 which will act as a spill-way in the event of there being too much fuel thrown into the venturi.

When an engine is running idle or on very slow speeds, say equivalent to a vehicle speed of ten miles an hour or slower and the throttle is suddenly thrown wide open, air being much lighter than the fuel will reach the engine before the required amount of fuel or gas does. The result is evidently that of providing too "lean" or "poor" a mixture for the first two or three explosions and the engine will therefore stall. This same condition arises when the engine is started and the throttle thrown suddenly open after it has been closed or when the device is operating under very slow speeds and the throttle is suddenly thrown open. To counteract these effects, there is provided a special feed which consists of a reservoir chamber 40 (see Fig. 5) which is open to atmosphere through a vent 41 above the level of the fuel in the float feed chamber and open to the fuel through a small orifice 42. This chamber communicates through a duct 43 with the venturi at a point substantially identical with that of the fuel level. The opening 42 is slightly below the fuel level of the float feed chamber and is comparatively small.

When the engine is idling or running very slowly, the suction in the venturi amounts to practically nothing and therefore there will be no drawing of fuel from the mouth of the opening 43 and chamber 40. How-

ever, fuel will percolate into the chambers 40 and 43 and they will be kept filled through the small opening 42.

In the event of the throttle being suddenly thrown wide open, the suction in the venturi will drain both the chamber 40 and channel 43 and thus, there will be furnished additional fuel which will allow the motor to pick up very rapidly. As soon as the reservoir 40 is drained, the only fuel which can possibly be drawn up through a small duct 43 is that which very slowly percolates through the opening 42 and this is not nearly sufficient to affect the mixture drawn in through the regular channels of the stand-pipe and appurtenant chambers. The chamber 40 and its channel 43 are also efficacious in starting the engine as, of course, under the immediate suction, they will furnish fuel to properly enrich the mixture.

The amount of fuel passed through the stand-pipe and quill may, of course, be adjusted as heretofore proposed by raising or lowering the stand-pipe 28 and changing the degree of registration of the perforations 33 and 26.

Unusual and astonishing results can be attained with this combination of ducts and channels. An absolutely even mixture may be secured at all speeds and a quick acceleration or "pick-up" is effected without intermediate points of poor mixture such as are customary with carburetors of the non-moving part type. Any mixture desired may be secured at any speed by merely changing the perforations 33, 26. By placing additional holes at the top or increasing their size by adjustment, a richer mixture is secured for high speeds than at lower speeds.

40 By adding holes or increasing the size at the bottom within the chamber 21, a richer mixture is secured on low speeds than at the high speeds and by increasing the number of holes or orifices at the center, that is, intermediate the uppermost holes of the stand-pipe and the lowermost ones, a richer mixture is secured for all intermediate speeds than the highest and lowest.

Each hole seems to control mixture for some particular speed and therefore by proper adjustment, any mixture can be secured for any speed.

As illustrated herein and in practice, it has been found that very good results are attained by using, for instance, in a one inch carburetor for a twenty horse power engine some twelve holes. It will be observed that the placing of holes in the stand-pipe ranges from well below the natural level in the chamber 21 to a point nearly up to the top of the venturi and of course by adjusting the size of the orifices, more or less suction may be induced in the stand-pipe. Therefore, the flow into the pipe through the orifices below the fuel level may

be modified. It is also quite apparent that an adjustment and arrangement of the openings must show marked results in the character of the mixture. This arrangement of stand-pipe when combined with the wells 70 and by-pass ducts described, gives a most efficient carbureting device and one which will produce a properly attenuated mixture for any and all speeds, at the same time, providing for easy starting of the engine when 75 cold.

It will be noted that the chamber 21 has a comparatively large surface opening at its outlet 25 which is directly in the venturi and therefore provides for the picking up of 80 a considerable volume of fuel when there is sufficient suction in the venturi. This chamber 21 is replenished by the flow through the openings 26, 33 of the stand-pipe and quill. As the suction increases in the venturi and withdraws the fuel from the orifices in the stand-pipe above the base thereof and depletes the fuel contained in the chambers 21, 25, more fuel will be drawn into the next succeeding orifice below the bottom 90 of the venturi. It will be seen from this that there is a sort of compensating action dependent upon the degree of suction between the quantity of fuel taken out of the orifices of the stand-pipe and that contained 95 in the well or chambers 21, 25.

It is apparent that the exact form of device illustrated and described may be departed from to a great extent without departing from the spirit or intent of the invention and the exact arrangements of ducts and chambers may be modified to suit any particular construction desired or for any demand which is required upon the carbureting mechanism.

What I claim as my invention and desire to secure by Letters Patent is:

1. In a carburetor having an automatically controlled fuel chamber, a venturi, a fuel well having an enlarged opening at its junction with the venturi and having a reduced portion extending to a considerable depth below the venturi and more closely surrounding the stand-pipe, a stand-pipe separating said well from the fuel supply, 110 said stand-pipe having openings within the well and openings above the well within the venturi, said openings being successively subject to the suction of the venturi as the level of the liquid is lowered in the well. 115

2. In a carburetor having an automatically controlled fuel chamber, a venturi, a fuel well extending below the venturi, a stand-pipe separating said well from the fuel supply, said stand-pipe having openings within the well and above the well within the venturi and means for adjusting 125 said openings.

3. In a carburetor having an automatically controlled fuel supply, a venturi, a 130

- stand-pipe open to the atmosphere and communicating with the fuel supply, said stand-pipe having openings above and below the bottom of the venturi and means for adjusting the size of the openings. 8. A carbureter having a float feed chamber under atmospheric pressure, a venturi, a stand-pipe forming a fuel connection from the float feed chamber to the venturi and surrounded by a well of substantial depth 50 extending from the bottom of the stand-pipe to the venturi, a chamber of comparatively small area, as compared with the well, communicating with the venturi above said well and having an inlet to the fuel supply 55 below the level of the fuel in the float feed chamber, said chamber being open to atmospheric pressure.
4. In a carbureter having an automatically controlled fuel supply and a venturi, a stand-pipe extending through said venturi and communicating with the oil supply, a well surrounding said stand-pipe and separated from the oil supply by said stand-pipe, adjustable openings intermediate the stand-pipe well and venturi, and an adjustable hollow spindle for adjusting and feeding fuel to the openings. 9. In a carbureter having a fuel supply, a venturi, means for supplying fuel to said venturi under varying degrees of suction, said means including a fuel supply well open to the venturi, a stand-pipe having perforations for feeding said well, a by-pass communicating with said well and with one end 60 of the venturi and a chamber fed from the oil supply and communicating with the venturi exteriorly of the oil well stand-pipe and by-pass.
5. In a carbureter, an automatically controlled fuel supply, a venturi, an oil supply nozzle in the form of a stand-pipe extending from the oil supply to the venturi, a fuel well extending below the venturi and surrounding the stand-pipe, said well having an enlarged opening at its junction with the venturi and being of substantial depth 65 in reduced diameter below said opening, and a by-pass chamber communicating with the fuel supply and the venturi above the fuel well. 10. In a carbureter having a fuel supply 70 and a venturi and a throttle valve for controlling the suction in the venturi, of means adjacent to the throttle including an open fuel duct for supplying fuel with air of abnormally low suction passed through the 75 venturi, independent means including a well and stand-pipe for supplying fuel upon varying suction through the venturi and means embodying a direct connection intermediate the supply and venturi for supplying an additional supply of fuel upon abnormally high suction in the venturi, all of said means embodying chambers, by-passes and wells uncontrolled by moving parts.
6. In a carbureter having a fuel supply, a venturi, a stand-pipe communicating with the venturi and the fuel supply, a fuel well open to the venturi and surrounding the stand-pipe for a substantial portion of its length and a chamber open to the fuel supply and opening to the venturi above the well. 7. In a carbureter having a fuel supply, a venturi, a stand-pipe communicating with the venturi and the fuel supply, a fuel well having an enlarged opening into the venturi 80 and surrounding the stand-pipe for a substantial portion of its length, a chamber open to the fuel supply and the venturi, a throttle valve at one end of the venturi and a by-pass communicating with the fuel well 85 and opening adjacent to the throttle valve.

JOSEPH C. COULOMBE.
